UNITED STATES PATENT OFFICE.

JAKOB THEEMLING, OF LOS ANGELES, CALIFORNIA.

ROTARY ENGINE.

1,327,575.

Specification of Letters Patent.

Patented Jan. 6, 1920.

Application filed December 30, 1918. Serial No. 268,889.

To all whom it may concern:

Be it known that I, JAKOB THEEMLING, a citizen of the United States, residing at Los Angeles, in the county of Los Angeles and State of California, have invented new and useful Improvements in Rotary Engines, of which the following is a specification.

This invention relates to improvements in rotary engines and pertains particularly to 10 the type comprising a rotor provided with an annular channel and a stator, there being abutments in said channel movable to and from each other.

The principal objects of this invention are 15 first, to provide a rotary engine requiring no valves; second, to provide an engine having positively actuated parts; third, to provide an engine which may have a plurality of motive chambers all embodied in a single 20 channel; and fourth, to provide an engine with a movable abutment of a novel construction.

This invention is particularly adapted for embodiment in an internal combustion engine, and in such specific form, the objects are first, to provide an engine with separate 25 compression and motive chambers; and second, to provide an engine which may have chambers so that one or more impulses are 30 imparted to the rotor during a single revolution.

In addition to the broader features of this invention, it is an object thereof to provide 35 a compact engine combining high capacity, ease and economy of operation, with great efficiency and power, and having no delicate or intricate mechanism.

An embodiment of my invention is illustrated in the accompanying drawings, in 40 which:

Figure 1 is a face view of the engine. Fig. 2 is an enlarged section taken on the line 2-2 of Fig. 1, the right hand half showing the section through the equalizing piston. In subsequent figures the rotor is not shown in the same relative position as in Fig. 2. Fig. 3 is a face view of the rotor taken in section on the line 3-3 of Fig. 2. Fig. 4 is an enlarged section taken on the line 4-4 of Fig. 1, showing the yielding piston and its co-operating parts. Fig. 5 is a section taken on the line 5-5 of Fig. 1. Fig. 6 is an enlarged section taken on the line 6-6 of Fig. 3. Fig. 7 is an enlarged

section taken on the line 7-7 of Fig. 3, and 55 Fig. 8 is an enlarged section taken on the line 8-8 of Fig. 1. Fig. 9 is an enlarged view of the piston illustrated in Fig. 8, showing the details of the packing. Fig. 10 is an enlarged section taken on the line 10-10 of Fig. 9; and Fig. 11 is an enlarged section taken on the line 11-11 of Fig. 9. Fig. 12 is a fragment of a follower ring.

Referring more particularly to the drawings, the shaft of the engine is indicated by 65 12 and keyed thereon is the rotor. The rotor has a spider 13, to the arms of which is secured a ring having piston chambers formed therein. The ring is formed of two 70 castings 14 and 15 held together by bolts 16 extending through internal flanges. The ring is constructed so that open ways are formed from the inner side to the periphery to allow for bolting the halves together, for the passage of exhaust gas and for the circulation of air. As shown herein, the engine has twin sets of piston and compression chambers, one set on each face of the 75 rotor co-operating with a set of parts on the stator. As these sets of chambers are duplicates, only one set will be described in detail. On the side face of the rotor adjacent the periphery is an annular compression chamber 17, which is semi-circular in radial section. A motive or firing channel 80 85 18, circular in section, is formed on the face of the rotor. Spaced 120° apart within the compression channel are stationary abutments 19, 19' and 19'', all hereafter referred to generally as abutments 19. Placed within the motive channel 18 are three abutments 20, 20' and 20'', all hereafter referred to generally as abutments 20. As the abutments 19 and 20 are similar only one will be described.

It will be noted, however, that 95 the abutments 20 are slightly in advance of the abutments 19, the direction of rotation of the rotor being indicated by the arrow A in Fig. 3.

Referring to Figs. 2, 3, 4 and 7, each abutment is a block fitted into its channel, and in co-operation with the yielding abutments divides the channels into separate chambers. Referring particularly to Figs. 3 and 4, the abutments have faces 23 and 24 sloping 100 from the bottom of the channel to the top having a rounded raceway for passage of the heads of the yielding pistons. If the 105

race-way were not formed, there would be a point of contact of the piston with the abutment, which would rapidly wear the piston or abutment so that an opening would be formed either at the end of the piston, when it rested in the bottom of the channel, or at the top of the abutment, thereby permitting leakage. Mounted in the abutment at the top thereof is a packing strip 25, to maintain a gas tight fit and take care of expansion and contraction. In Fig. 2 the packing strip is indicated by 91 and the leaf spring holding it in outer position by 92. The abutments 19 and 20 are held in position by means of bolts, as indicated by 26 in Figs. 2 and 4. Between the channels 17 and 18 on the face of the ring is a flat surface having annular packing rings 27 and 28 placed adjacent the channels. Pairs of transverse packing strips are disposed on the flat face, each pair being 120° apart, providing means which prevents travel of gases around the rotor between the rotor and the inner wall of the stator. Leading from the channel 18 at the abutments are intake passages 30. These passages lead to elongated port openings, in the face of the rotor separately indicated by 31, 31' and 31''. Each port opening is located between a pair of transverse packing strips. Equalizing ports 32 as shown in Fig. 7 connect the port openings on opposite faces of the rotor. In the firing channel 18 forward of the abutments 20 are exhaust ports 33, 33' and 33''. These open to the interior hollow space of the rotor ring, the exhaust passing thereto as illustrated by the arrows *e* in Fig. 6. Near the inner and outer edges of the rotor face are annular packing rings 34 and 35.

The stator is a casting formed of two halves bolted together to form a housing 36 for the rotor, and is provided with arms 37 which have bearings 38 for the shaft 9. Formed on the housing are heat radiating fins 39. Mounted on the inner wall of each half of the stator are follower rings 21 and 22 having rounded transverse sections and fitting within the rounded raceway at the top of the abutments 19 and 20. The follower rings may be made in sections extending from piston to piston, having a rib at the center and being provided with stems 40. As the follower rings are similar only one will be described. Stems 40 extend through openings in the stator and have threaded ends upon which nuts 41 are mounted. Between washers on each stem are springs 42 tending to hold the follower ring against the face of the stator.

Mounted on the stator and registering with the firing channel 17 are yielding abutment pistons. Referring particularly to Figs. 1, 2, and 4, cylinders 43 are secured to a finishing pad on the stator and have a

liner section 44 provided with suitable snap rings to provide a gas tight fit between the cylinder wall and the liner. The lower face of the liner section 44 bears upon the face of the rotor. The upper face of the liner section is beveled, and mounted thereon is a liner section 45 having an inwardly extending shoulder 46 provided with ports 47. Holding the liner sections in position is a ring nut 48, which is threaded into the cylinder and bears upon the top of the liner sections. Slidingly mounted within the liner is a yielding piston 49 having a hemispherical head, which rides in the channel 18. The rounded end is packed by a snap ring 50 extending transverse to the channel. This provides for a tight fit on the abutment in the channel. To provide for a tight fit within the liner snap rings 51 are mounted upon the piston. Referring particularly to Figs. 9, 10 and 11, the rounded head of piston 73, which is packed similar to piston 49 is slotted as indicated by 52. Disposed in the slot 52 is a carrier plate 53 having a bore 54 disposed eccentric thereto. Mounted on the periphery of the plate 53 is the snap ring 50. The overall diameter of the snap ring is substantially that of the rounded head of the piston, but the ring is expanded sufficient to make a tight fit with the channel. In the piston and transverse thereto is a bore 55 for registration with the bore 54, and extending through bores 54 and 55 is a pin securing the carrier plate to the piston, thus, allowing a swinging movement to accommodate the packing to the channel. Referring again to piston 49, the upper end of the piston is reduced in diameter as indicated by 55, and an enlargement 56 of the piston slides in the ring nut 48. This construction provides for an air space 57 to form a cushion for holding the piston on the bottom of the channel. It will be noticed that the diameter of enlargement 56 is less than the diameter of the liner. When the space 57 is filled with air under pressure through a port 58 adapted to be attached to an air tank, there will be a force acting upon the lower shoulder of the abutment tending to hold the abutment in its lower position, and a force due to the same pressure acting upon the shoulder formed by enlargement 56 tending to force the abutment into its upper position. Due to the larger area of the lower shoulder, the resultant force acting upon the abutment will be the difference of the two forces before mentioned and will hold the abutment in its lower position. The piston rod carries a pin 59. Pivots secured to the pin 59 is a rocker arm 60, which is pivotally mounted upon a standard 61. Standard 61 is preferably formed as a part of the cylinder casting 43. On the opposite side of the standard to the cylinder and preferably cast 130

therewith is a cylinder 62, which opens through the foundation plate to the channel 18. Slidably mounted in the cylinder 62 is a piston 63. A connecting rod 64 secures 5 the piston 63 to the rocker arm 60.

The yielding pistons for the compression channel have cylinders 65 opening to the compression channel 17. Mounted in each cylinder is a suitably packed liner section 10 66 having a beveled upper face, and a liner section 67 bearing on said beveled upper face. Liner section 67 has a shoulder 68 formed at its upper face and bearing thereon is a section 69 of a smaller internal diameter than the liner sections 66 and 67. Liner section 69 is provided with an inward offset 70, from which extends a tubular portion 71 of reduced diameter. Holding the liner section in place is a ring nut 72 threaded in the cylinder 65. Slidably mounted within the sections 66 and 67 is a yielding abutment piston 73 packed in a manner similar to the yielding abutment piston 49. A stem 74 of reduced diameter provides an 25 air cushion space 75 around the stem. Above the shoulder 68, the stem has an enlargement 76 which slides in section 69. The stem is reduced in diameter as indicated at 77 and rides within the tubular extension 30 71. Suitable packing is provided to make a tight fit. A port opening 78 communicates with the cushion 75 and is adapted for connection to a reservoir containing air under pressure so as to provide an air 35 cushion. The space 79 between the liner section 67 and the stem 74 provides a balance chamber which communicates through an equalizing port 80 with the compression chamber 17 and assists in holding the yielding abutment piston against the channel 40 with a pressure proportional to the pressure within the channel.

Referring particularly to Figs. 1 and 7, a port 81 in the side wall of the stator is 45 indicated. Port 81 connects with a port 82 in the foundation plate for the yielding abutment piston cylinder. This port 82 communicates with a port 83 in the wall of the stator and leads to the compression chamber. Disposed within the port 81 is a bushing 84 bearing upon the face of the rotor and held against the face by a spring 85, thereby making a tight fit with the face. There are three sets of the ports and 50 passages just described located 120° apart, and each set constitutes an intake passage for the firing channel.

Referring particularly to Figs. 1 and 5, a port for the admission of gas to the compression chamber is indicated by 86 and 60 communicates with an inlet 87. There are three such ports indicated severally by 86, 86' and 86''. All inlets 87 are connected to a single carburetor.

65 Spark plugs 88 one for each of the firing

chambers are disposed forward of the yielding abutment and open to the firing channels.

Assume that the rotor is moving in the direction of the arrow A in Fig. 3, the abutment 19 arrives under the piston 73, and the latter finally reaches the top of the former. Upon the further movement of the rotor, a closed space is formed between 73 and abutment 19, which space increases in volume. 70 A charge of gas is drawn through the intake port 86 until the piston 73 and abutment 19' are in registry. This action has occurred in all of the compression chambers, and assuming the engine has been operating, there 75 would have been a charge of gas between the piston 73 and the stationary abutment 19'. The charge in the space between the piston 73 and abutment 19' will be compressed by reason of the abutment 19' moving toward the piston 73 and thereby decreasing the volume of the space. As abutment 19' approaches near the piston 73, the port 31' will register with compression port 82. This establishes communication 80 between the compression chamber and the firing chamber in channel 18, the compressed charge entering the firing channel between the abutment 20' and the piston 49. After the port 31' has passed out of registration with compression port 82, the charge 85 is fired by the spark plug creating an impulse which reacts upon the stationary abutment 20 and causes it to move away from the yielding piston 49. The exhaust port 100 33' finally passes under the abutment 49 and connects the firing chamber with the hollow space of the rotor ring and passing to the atmosphere through exhaust outlets 89, there being openings 90 in the periphery of 105 the rotor ring as indicated in Fig. 2. The path of the exhaust gases is indicated by arrows e. The burnt gases are then swept out of the chamber by reason of the abutment 20'' approaching the piston 49. The 110 action just described occurs in all three firing chambers and their co-operating compression chambers. It will be noted that firing occurs in each firing chamber three times in one revolution. By increasing the 115 number of abutments and pistons the number of impulses during a single revolution may be increased.

The compression piston is held in position upon the bottom of the channel by means of 120 the air cushion formed around stem of the abutment, which holds the piston in the channel, together with the pressure which enters from the compression chamber through port 80 and is therefore proportionate to the pressure within the chamber and equalizes the pressure of compression tending to force the piston out of the channel.

The yielding abutment piston in the firing chamber is held upon the bottom of the 125 130

channel by the air cushion, which holds the piston in the channel, together with the pressure transmitted from the equalizing piston. The explosion in the firing chamber acts upon the equalizing piston holding the latter upon its seat with a pressure proportionate to the pressure of explosion.

What I claim is:

1. In a rotary engine, the combination of 10 a rotor element and a stator element, an annular channel formed in one of said elements, an abutment dividing said channel, a piston abutment slideable into said channel, resilient means tending to hold said 15 piston abutment in said channel with a uniform pressure, and means operated by the impulse pressure of the motive fluid tending to hold said piston abutment in said channel, one of said abutments being fixed 20 to said rotor and the other of said abutments being fixed to said stator, a port on said rotor opening to said channel for the intake of motive fluid, an intake passage in said stator for registration with said port, 25 and an exhaust port on said rotor opening into said channel.

2. In a rotary engine, the combination of a rotor having an annular chamber, an abutment fixed in and dividing said channel, 30 a piston on said stator slideable into said channel, resilient means tending to hold said piston in said channel with a uniform pressure, and means operated by the impulse pressure of the motive fluid tending to hold 35 said piston in said channel, a port on said rotor opening to said channel for the intake of motive fluid, an intake passage in said stator for registration with said port, and an exhaust port on said rotor opening into 40 said channel.

3. In a rotary engine, the combination of a rotor having an annular chamber, an abutment fixed in and dividing said channel, an abutment piston on said stator slideable into 45 said channel, resilient means tending to hold said piston in said channel, an equalizing cylinder opening to said channel in advance of said abutment piston, an equalizing piston in said equalizing cylinder, means connecting said equalizing piston and said abutment piston so that the impulse pressure of the motive fluid in the channel will tend to hold 50 said abutment piston in said channel, a port on said rotor opening to said channel for the intake of motive fluid, an intake passage in said stator for registration with said 55 port, and an exhaust port on said rotor opening into said channel.

4. In a rotary engine the combination of 60 a rotor having a half round annular channel, an abutment fixed therein having sloping sides and a rounded raceway, a yieldable piston on said stator, said piston having a ball end disposed in said channel and arranged to ride through said race-way, a

port on said rotor opening to said channel for the intake of motive fluid, an intake passage in said stator for registration with said port, and an exhaust port on said rotor opening into said channel.

70

5. In a rotary internal combustion engine, the combination of a rotor element and a stator element, an annular compression channel and an annular firing channel being formed in one of said elements; a compression abutment in said compression channel dividing the latter, a yieldable compression abutment in said compression channel, one of said abutments being fixed to said rotor and the other of said abutments being fixed to said stator; a firing abutment in said firing channel dividing the latter, a yieldable firing abutment in said firing channel, one of said abutments being fixed to said rotor and the other of said abutments being fixed to said stator; a compression passage in said stator communicating with said compression channel at the rear of the compression abutment fixed to said stator, said compression passage being open to the face of 80 said rotor, an intake passage in said rotor communicating with said firing channel at the rear of the firing abutment fixed to said rotor and opening on the face of said rotor for registration with said compression passage, and an exhaust port on said rotor opening into said firing channel.

85

95

6. In a rotary internal combustion engine, the combination of a rotor element and a stator element, an annular compression channel and an annular firing channel formed in one of said elements; a compression abutment in said compression channel dividing the latter, a yieldable compression abutment in said compression channel, one of said abutments being fixed to said rotor and the other of said abutments being fixed to said stator; a firing abutment in said firing channel dividing the latter, a yieldable firing abutment in said firing channel, one of said abutments being fixed to said rotor and the other of said abutments being fixed to said stator; the abutment in said firing channel fixed to said rotor being in advance of the abutment in said compression channel fixed to said rotor, the abutment in said firing channel fixed to said stator being to the rear of the abutment in said compression channel fixed to said stator; a compression passage in said stator communicating with 100 said compression channel at the rear of the compression abutment fixed to said stator, said compression passage being open to the face of said rotor, an intake passage in said rotor communicating with said firing channel at the rear of the firing abutment fixed to said rotor and opening on the face of said rotor for registration with said compression passage, and an exhaust port on said rotor opening into said firing channel.

105

110

115

120

125

130

7. In a rotary internal combustion engine, the combination of a rotor having an annular compression channel and an annular firing channel; a compression abutment on said rotor dividing said compression channel, a firing abutment on said rotor dividing said firing channel; a stator having a yieldable compression piston disposed in said compression channel, a yieldable firing piston on said stator disposed in said firing channel; a compression passage in said stator communicating with said compression channel at the rear of said compression piston, said compression passage opening to the face of said rotor, an intake passage in said rotor communicating with said firing channel at the rear of said firing abutment for registration with said compression passage, and an exhaust port on said rotor opening into said firing channel.

8. In a rotary internal combustion engine, the combination of a rotor having an annular compression channel and an annular firing channel; a compression abutment on said rotor dividing said compression channel, a firing channel; said firing abutment being in advance of said compression abutment; a stator having a yieldable compression piston disposed in said compression chamber, a yieldable firing piston on said stator disposed in said firing channel, said yieldable firing piston being to the rear of said yieldable compression piston; a compression passage in said stator communicating with said compression channel at the rear of said compression piston, said compression passage opening to the face of said rotor, an intake passage in said rotor communicating with said firing channel at the rear of said firing abutment for registration with said compression passage, and an exhaust port on said rotor opening into said firing channel.

9. In a rotary internal combustion engine, the combination of rotor having an annular compression channel and an annular firing channel, a compression abutment on said rotor dividing said compression channel, a firing abutment on said rotor dividing said firing channel; a stator having a yieldable compression piston disposed in said compression chamber, a firing piston on said stator disposed in said firing channel, resilient means tending to hold said compression piston in its channel with a uniform pressure, means operated by the pressure of the exploded charge tending to hold said firing piston in its channel; an inlet port in said stator communicating with said compression channel forward of said compression piston, a compression passage in said stator communicating with said compression channel at the rear of said compression piston, said compression passage opening to the face of said rotor; an intake passage in said rotor communicating with said firing channel at the rear of said firing abutment for registration with said compression passage, and an exhaust port on said rotor opening into said firing channel.

rotor communicating with said firing channel at the rear of said firing abutment for registration with said compression passage, and an exhaust port on said rotor opening into said firing channel.

10. In a rotary internal combustion engine the combination of a rotor having an annular compression channel and an annular firing channel, a compression abutment on said rotor dividing said compression channel, a firing abutment on said rotor dividing said firing channel, said firing abutment being in advance of said compression abutment; a stator having a yieldable compression piston disposed in said compression chamber, a firing piston on said stator disposed in said firing channel, said firing piston being to the rear of said compression piston, resilient means tending to hold said compression piston in its channel with a uniform pressure, means operated by the pressure of the exploded charge tending to hold said firing piston in its channel; a compression passage in said stator communicating with said compression channel at the rear of said compression piston, said compression passage opening to the face of said rotor; an intake passage in said rotor communicating with said firing channel at the rear of said firing abutment for registration with said compression passage, and an exhaust port on said rotor opening into said firing channel.

11. In a rotary internal combustion engine, the combination of a rotor having an annular compression channel and an annular firing channel, a compression abutment on said rotor dividing said compression channel, a firing abutment on said rotor dividing said firing channel; a stator having a yieldable compression piston disposed in said compression channel, a firing piston on said stator slideable into said firing channel, an equalizing piston cylinder on said stator opening to said firing channel in advance of said firing piston, resilient means tending to hold said firing piston in said channel with a uniform pressure, an equalizing piston in said cylinder, means connecting said equalizing piston and said firing piston so that pressure in said firing chamber will tend to hold said firing piston in its channel; an inlet port in said stator communicating with said compression channel forward of said compression piston, a compression passage in said stator communicating with said compression channel at the rear of the compression piston, said compression passage opening to the face of said rotor, an intake passage in said rotor communicating with said firing channel at the rear of said firing abutment for registration with said compression passage, and an exhaust port on said rotor opening into said firing channel.

12. In a rotary internal combustion en-

gine, the combination of a rotor having an annular compression channel and an annular firing channel, a compression abutment on said rotor dividing said compression channel, a firing abutment on said rotor dividing said firing channel, said firing abutment being in advance of said compression abutment; a stator having a yieldable compression piston disposed in said compression channel, a firing piston on said stator slidable into said firing channel, said firing piston being to the rear of said compression piston, resilient means tending to hold said firing piston in said channel with a uniform pressure, an equalizing piston cylinder on said stator opening to said firing channel in advance of said firing piston, an equalizing piston in said cylinder, means connecting said equalizing piston and said firing piston so that pressure in said firing chamber will tend to hold said firing piston in its channel, an inlet port in said stator communicating with said compression channel forward of said compression piston, a compression passage in said stator communicating with said compression channel at the rear of the compression piston, said compression passages opening to the face of said rotor, an intake passage in said rotor communicating with said firing channel at the rear of said firing abutment for registration with said compression passage, and an exhaust port on said rotor opening into said firing channel.

13. In a rotary internal combustion engine, the combination of a rotor having an annular compression channel and an annular firing channel, a compression abutment on said rotor dividing said compression channel, a firing abutment on said rotor dividing said firing channel, said firing abutment being in advance of said compression abutment; a stator

having a compression piston disposed in said compression channel, said piston being disposed in a cylinder provided with a balance chamber communicating with said compression channel at the rear of said piston, a firing piston on said stator slidable into said firing channel, said firing piston being to the rear of said compression piston, resilient means tending to hold said firing piston in said channel with a uniform pressure, an equalizing piston cylinder in said stator opening to said firing channel in advance of said firing piston, an equalizing piston in said cylinder, means connecting said equalizing piston and said firing piston so that pressure in said firing chamber will tend to hold said firing piston in its channel, an inlet port in said stator communicating with 45 said compression channel forward of said compression piston, a compression passage in said stator communicating with said compression channel at the rear of the compression piston, said compression passage 50 opening to the face of said rotor, an intake passage in said rotor communicating with said firing channel at the rear of said firing abutment for registration with said compression passage, and an exhaust port on said rotor opening into said firing channel.

14. A piston having a rounded head with a transverse slot therein, a carrier plate pivotally mounted in said slot, and a snap ring mounted on said carrier plate.

15. A piston having a rounded head with a transverse slot therein, a circular carrier plate eccentrically and pivotally mounted in said slot, and a snap ring mounted on said carrier plate.

In witness that I claim the foregoing I have hereunto subscribed my name this 24th day of December, 1918.

JAKOB THEEMLING.
